(57) **CLAIM**

The ornamental design for a beverage dispenser, as shown and described.

DESCRIPTION

FIG. 1 is a front, top perspective view of a beverage dispenser showing my new design in a closed configuration; FIG. 2 is a front elevation view of the new design in the closed configuration;

FIG. 3 is a rear elevation view of the new design in the closed configuration;

FIG. 4 is a left side view of the new design in the closed configuration;

FIG. 5 is a right side view of the new design in the closed configuration;

FIG. 6 is a top plan view of the new design in the closed configuration;

FIG. 7 is a bottom view of the new design in the closed configuration;

FIG. 8 is a front, top perspective view of the new design in an open configuration; and,

FIG. 9 is a right side view of the new design in the open configuration.

The broken lines in the drawing depict portions of the beverage dispenser that form no part of the claimed design.
